United States Patent Office.

PASCHAL CONVERSE, OF NEW HAVEN, CONNECTICUT.

Design No. 3,098, dated July 14, 1868.

DESIGN FOR A CLOCK-CASE.

The Schedule referred to in these Letters Patent and making part of the same.

TO ALL WHOM IT MAY CONCERN:

Be it known that I, PASCHAL CONVERSE, of New Haven, in the county of New Haven, and State of Connecticut, have invented a new Design for a Clock-Case; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view, and in

Figure 2 a transverse section.

This invention relates to a design for a wood clock-case, which consists in the ornamentation of the vertical angles of the case by an imitation impost, and by the arrangement of a gilt or colored moulding around the door-opening of the front.

In order to the clear understanding of my invention, I will fully describe the same, as illustrated in the accompanying drawings.

The case proper is composed of a base, A, case B, and projecting top, C. The two front angles of the case are rounded to represent an impost, as seen in fig. 1, and also in section, and around the door is a moulding, D, of gilt or different-colored wood from the front, E, of the case, as shown in the drawing.

Having described my invention, what I claim as new, and desire to secure by Letters Patent, is—

The design for a clock-case, herein set forth and illustrated.

PASCHAL CONVERSE.
